UNITED STATES PATENT OFFICE.

FRANK C. WHITE, OF MERIDEN, CONNECTICUT, ASSIGNOR TO WILCOX & WHITE COMPANY, OF MERIDEN, CONNECTICUT, A CORPORATION OF CONNECTICUT.

AUTOMATIC PIANO-PLAYER.

SPECIFICATION forming part of Letters Patent No. 697,226, dated April 8, 1902.

Application filed November 26, 1901. Serial No. 83,746. (No model.)

To all whom it may concern:

Be it known that I, FRANK C. WHITE, a citizen of the United States, residing at Meriden, in the county of New Haven and State of Connecticut, have invented new and useful Improvements in Automatic Piano-Players, of which the following, together with the accompanying drawings, is a specification sufficiently full, clear, and exact to enable persons skilled in the art to which this invention appertains to make and use the same.

My present invention relates to the fingers or playing-lever mechanism and to the structural organization of the mechanism in a manner to facilitate adjustment of the fingers or playing-levers to different positions in height relatively to their operating mechanism and the body-casing.

Among the various styles of pianos manufactured and in use there exist many differences in the height of the manual or keyboard from the floor, the extreme variation amounting to some four and one-half inches, more or less, in different pianos. To accommodate these differences in heights of keyboards and to render the construction of an automatic piano-player when manufactured such as will suit any piano regardless of the height of its manual-keyboard by a simple adjustment of the playing devices or finger-bed and without necessitating the raising or lowering of the main action, body, or case of the piano-player instrument is the prime object of my invention.

Another object is to provide an automatic piano-player with means for shifting or adjusting its system of fingers or playing-levers to different heights or levels independently of the action or finger-actuating mechanisms and body-easing of the piano-playing instrument.

Another object is to provide adjusting means that will afford a skew adjustment of the series of fingers or the regulation of said fingers to differences in level at the respective ends of the keyboard irrespective of the level of the finger-operating mechanism and effective at the several positions of height adjustment.

Another object is to render the series of fingers or playing-levers disengageable from

their lifters or actuating-pitmen and to afford means for shifting the fulcrum-supports of the series and for maintaining the disengaged parts in proper relation for the reengagement of the fingers with the lifters or actuating-pitmen at the higher or lower position of adjustment.

Another object is to provide, in a piano-player provided with a system of organ-reeds or sound-producing devices and a series of fingers or playing-levers that are adjustable to different heights in relation to the finger-operating mechanism, means for stopping or throwing said fingers out of engagement with the piano manual-keys while playing, as hereinafter explained.

Another object is to provide a finger-lever in a piano-player with an adjustable presser-head or finger-tip having an attaching-spring and an adjusting means for regulating the same.

Minor objects and the especial features of my invention are set forth in the following detailed description, the particular subject-matter claimed being hereinafter definitely specified.

In the drawings, Figure 1 represents an automatic piano-player embodying my invention, certain parts being shown in section. Fig. 2 represents a back view of the improved mechanism, the ends of the fingers being in section. Fig. 3 represents a plan view of the playing mechanism. Fig. 4 is a sectional view showing the finger and evener-bar. Fig. 5 represents the under side of one finger and a top view of the spring-attached presser-head or tip. Fig. 6 represents, on a somewhat larger scale, a vertical section of the invention as applied in a piano-player comprising a reed-organ attachment. Fig. 7 represents a vertical section through one of the adjustable supporting-bearings at the end of the finger-bed or fulcrum-bar. Fig. 8 represents a rear view at one end of the fulcrum-bar. Fig. 9 illustrates a modification in the manner of hanging the fulcrum-bar, showing a swinging in lieu of a sliding connection; and Fig. 10 illustrates a modification in the form of the lifter.

My present invention is applicable to automatic piano-players such as described in Let-

ters Patent No. 592,641, dated October 26, 1897, or to instruments of similar general character and purpose, and reference may be had to said Letters Patent for a full description of suitable means for effecting and controlling the movement of the puppets or actuating parts with which my present improvements are connected or combined for operation in practice.

10 The prime feature of my invention consists in so arranging and combining the fulcrum-bar or part that carries the finger-levers that the series of fingers can be adjusted up and down independently of the finger-actuating devices and pneumatic-operating mechanism and the finger-actuating devices operatively engaged at various convenient points or at any desired position within the limits of extreme adjustment, the finger-levers being operative with equal facility at any position of the adjustments, so that the instrument without change in the permanent relation of the pneumatic-action, bellows, and motor appliances within the case or without elevating or depressing the entire instrument-body can by a simple and convenient adjustment be readily adapted to suit the height of any piano-keyboard upon which the purchaser or user may desire to employ it.

15 20 25 30 35 40

In accordance with my invention the finger-bed or fulcrum-bar 3, on which the fingers or playing-levers 5 are fulcrumed, is arranged with its respective ends each supported by a hanger or bearing-piece 4, that is movable up and down on a rod or guiding device 6, sustained in upright position by a suitable standard or fixture 7, standing upon the chest P, which contains the operating-pneumatics, or upon some other stationary support. The guide-rod 6 may be endwise movable or rigidly fixed in its support.

The bearing-piece 4 is adjustable on the guide 6 and is provided with a set-screw 8 or means for securing it at any position of adjustment thereon. Said bearing-piece is best provided with a horizontally-projecting arm 14, upon which the end of the fulcrum-bar 3 is mounted in a manner to permit movement thereof toward and from the standards. A threaded collar-nut 13 is arranged on the set-screw 8 or other efficient means provided for securing the bar 3 rigidly against the shoulder of the bearing-piece and for releasing it when adjustment is to be effected.

55 The lifter pitmen or members 9 for operating the fingers 5 are in accordance with my invention constructed of considerable length and each provided with a series or plurality of notches and lugs or suitable detents 10, adapted for the interchangeable engagement of the ends 15 of the fingers, as hereinafter more fully explained. The lifters 9 in the present instance are arranged to stand directly upon the heads of the action-puppets I, their lower ends retained in proper working relation thereon by dowel-pins 11 or other suitable connecting devices, while their up-

per ends are movably supported in a guide-rail 12, secured to the guide-supporting brackets 7, and through which guide-rail said lifters 70 can freely slide endwise up and down in accordance with the music-controlled movements of the puppets I.

The action members or puppets I can be worked by the usual motor and operating-pneumatics within the chest P, controlled by a music-sheet passing over the tracker-range T. Such mechanism can be of any well-known or suitable construction adapted for imparting reciprocative impulses to the 80 puppets or actuating connections; but since it is not of my invention it need not be more fully herein set forth.

The tail ends of the fingers 5 are of a shape and dimension that will engage with the 85 notches or detents on the lifter-pitmen 9 and will conveniently disengage therefrom. Said ends are preferably cushioned or covered with felt to avoid rattling. Beneath the fingers 5, which are individually disposed in recesses in the bar 3 and fulcrumed, as at 2, there is a plate or bar 16, carrying the finger recoil-springs 17 and having at its front edge a bar, strip, or cushion 18, that serves as an evener for the series of fingers when they are 90 disengaged from the operating devices. The evener-bar may be formed as a part of the plate 16 or as a separate bar attached to the fulcrum-bar 3 and parallel therewith. At their striking ends the fingers 5 are each provided 100 with a spring-attached presser-head 25, that acts against the surface of the piano manual-key K. (See Figs. 1 and 6.) Said presser-head I construct as a semicylindrical block having its flat side secured to one end of a flat metal 105 spring-arm 24, the other end of said spring-arm being attached to the under side of the finger-lever 5 in such relation that the block or head is disposed in transverse position beneath the finger end, as best shown in Fig. 110 5, the rounded surface of the presser-head, which is provided with a felt-packed face, being downward. A screw 23 is arranged through the end of the fingers, with its point impinging against the attaching spring-plate 115 at the back of the block. The spring-arm serves for yieldingly attaching the presser-head and for keeping the head pressed upward toward the finger, while the screw serves therewith as a means for regulating the 120 presser-head to accurately meet the key-surface of an individual key.

When this invention is employed combined with a piano-player provided with a set of organ-reeds or sound-producing devices 20, 125 the tracker-pins 19 for operating the reed-duct valves 21 are preferably disposed upon the top ends of the lifters 9, the lifter-bar being provided with a depression or seat 22 for retaining the foot of the tracker-pin in place. 130 An example of this construction is shown at the left-hand end of Fig. 2 and in detail in Fig. 6.

When a reed-organ attachment is employed

in the piano-player, it is desirable to have a stop or throw-off for temporarily silencing the piano-action during some parts of the playing. In such instances I make the guide-rods 5 endwise movable in the bracket-ears of the standards and provide, in combination with said guide-rods upon which the bearings 4, that carry the finger-bed or fulcrum-bar 3, are mounted, a controllable means for raising 10 and depressing the guide-rods and parts supported thereon to a degree that will move the ends of the fingers 5 clear from the piano-keys without stopping the vibrations of the fingers. This mechanism, as shown, consists of 15 a spring 26, acting against the guide-rod and of sufficient tension to hold the parts normally elevated, and a depressing lever or device 27, arranged for action in opposition to said spring or springs for depressing said guide-rods and 20 fulcrum-bar to bring the fingers into playing contact with the piano-keys. Said lever or device 27 is combined with a suitable self-locking actuator device 28, operatively connected with a stop-pull 29 or equivalent 25 means at the hand of the operator for controlling the position of the guide-rods and connected parts. As herein arranged the spring 26 acts to throw the fingers out of contact and the depressing-lever 27 to throw them 30 into contact, accordingly as the stop is manipulated.

For adjusting the series of fingers 5, so that the piano-player will properly coincide with the height or level of the manual-keyboard of any particular piano, the operation 35 is as follows: The operator runs back the retaining devices or collar-nuts 13, thereby permitting the backward movement or retraction of the fulcrum-bar 3 sufficiently to disengage 40 the ends 15 of the entire series of fingers or playing-levers from the notches or detents 10 of the lifters 9. The set-screws 8 are then loosened and the bearings 4 shifted up or down upon the guides 6 to the desired position, 45 as from the position indicated by dotted lines 30 to that indicated by full lines in Fig. 6, and the ends of the fingers then reengaged with the appropriate notches or detents of the lifters or actuating mechanism, 50 then reclamping the fastening devices that secure the bearing-pieces 4 and fulcrum-bar 8 in place.

When the fingers are disconnected from their lifter mechanism, the ends of all the 55 fingers are caused to assume uniform alignment against the evener-bar 18, so that in adjusting the finger-bed to its new position the several fingers will enter into engagement with the respective lifters all at their proper 60 position.

In addition to the adjustment of the fingers to the different positions represented by the plurality of notches or detents of the lifters 9 a more precise adjustment is obtained by 65 sliding the hangers or bearing-pieces 4 upon the guides 6 to a higher or lower relation in respect to the particular point of engage-

ment of the finger ends with their lifting-detents 10, so that the striking ends of the fingers normally stand at a slight elevation or at 70 a slight depression relatively to the actual level of the engaged detents. Again, by raising and securing one of the bearing-pieces 4 on its guide above the level of the other bearing-piece on its guide a skew adjustment of 75 the fulcrum-bar and series of fingers is attained, so as to accommodate or counteract any variation in level between the respective ends of the piano-keyboard due to irregularities in the piano structure, or occasioned 80 by the instruments standing upon an uneven floor, or from other causes.

To facilitate the bringing of the finger ends 15 readily into conjunction with the several notches or detents on the lifters 9, I preferably form lugs or recesses 31 in the face of the standards 7 (see Fig. 7) and provide a spring-pressed stud 32 in the bearing-piece 4, that slightly catches into said recesses to indicate positions where the finger ends and 20 lifter-detents are at an engageable alignment with each other. Said spring-pressed studs 32 can, if desired, be made to exert sufficient force for temporarily supporting the parts at the place of adjustment. In some instances 25 these spring-pressed studs may be omitted, especially when it is desired to have the guide-rods 6 slide endwise in the bracket-ears, as above referred to.

Piano-playing fingers that are disengageably or variably connected with their actuating devices and adjustable in height of operating position relatively thereto may be employed in combination with operating mechanism in a musical self-playing attachment of 100 other construction than that above referred to, and I desire to include such combinations as within the scope of my invention.

In Fig. 9 I have illustrated a modification wherein the fulcrum-bar 3 is combined with 110 the bearing-piece 4 by a hinge-joint 33 and disengagement of the fingers 5 from the lifters attained by swinging instead of a sliding movement. Such modification is included as 115 within the scope of my invention.

In Fig. 10 I have shown a modification in the form of the lifter, which is therein shown as a thin bar 91, the detents being therein made as projecting pins 101 and the finger 51 engaging therewith by a bird-mouth slot, 120 as at 35, the action of this connection being substantially similar to that hereinbefore described.

What I claim as of my invention, and desire to secure by Letters Patent, is—

1. In an automatic piano-player, the combination with the body-casing, and pneumatically-controlled action devices or puppets; of finger-actuating members respectively provided with means for engagement of the playing-finger at various positions thereon, a series of detachably-engaged playing-fingers actuated thereby, and means for the support of said fingers adjustable for elevation and

depression within the casing, for changing the operating relation and height of the series of fingers with respect to the positions of engagement with the finger-actuating members, and to the pneumatically-controlled action devices.

2. An automatic piano-player having an independently-adjustable series of playing levers or fingers, in combination with the finger-operating mechanism, the fingers and operating devices having means for connecting and operating said fingers at different positions of height in relation to the actuating mechanism.

15 3. In an automatic piano-player, the combination, with the fingers, finger-bed and music-controlled action devices; of a series of finger-engaging lifters or pitmen respectively provided with a plurality of notches, lugs or detents engageable with said fingers, at different positions or height thereon, and means for adjusting the finger-bed for establishing engagement of the fingers with the lifter-detents, at different working positions.

25 4. The combination, with the fulcrum-bar, the player levers or fingers, and the upright standards or supporting-guides for the ends of said bar, of bearing-pieces adjustable up and down said guides, said bearing-pieces at 30 respectively provided with an arm whereon said fulcrum-bar is movably supported, means for confining said fulcrum-bar upon the arms, and devices for securing the bearing-pieces at adjustable position on the guides.

35 5. The combination of a lifter-pitman having a series of notches, lugs or projecting detents, a finger-lever adapted for detachably engaging therewith at its front end, a shiftable fulcrum-bar in which said finger is pivotally fulcrumed, supports for sustaining the bar and fingers, and means for releasing said fulcrum-bar for disengaging and reengaging said finger end with either of said lifter-detents, and means for securing said fulcrum-bar at the positions of adjustment.

40 6. In an automatic piano-player, the combination with actuating members and playing-fingers mutually engageable at steps or positions corresponding with notches or detents on the actuating members, and a movable fulcrum-bar carrying said fingers; of guides, and adjustable supporting devices for said fulcrum-bar adapted for adjusting and sustaining the fulcrum-bar and fingers at said 45 step positions, and for varying the adjusted relation of the finger-fulcrum to stand above or below the normal working level of the fingers as engaged at the respective notches or detents.

50 7. In an automatic piano-player, the combination of a movable fulcrum-bar, the series of playing-fingers fulcrumed thereon, guiding supports for the respective ends of said fulcrum-bar, and adjusting hangers or bearing-pieces connecting said fulcrum-bar to the guiding-supports, said bearing-pieces being 55 independently adjustable thereon at each end

of the bar, and adapted for permitting a skew or inclined adjustment of said bar and series of fingers relatively to the level of the action- 70 bed.

8. In an automatic playing attachment for manual musical instruments, comprising a pneumatically-operated action mechanism, a set of organ-reeds with valves and tracker-pins therefor, a series of manual playing-fingers, a fulcrumed bed or bar that is adjustable up and down to different working positions; the finger-actuating pitmen respectively having a plurality of notches or detents for engaging the finger, and provided with a seat for the end of said tracker-pin, and a foot-pin engaging the action-puppet, substantially as and for the purpose set forth.

9. In an automatic piano-player provided 85 with a set of organ-reeds or sound-producing devices, the combination, of the detented lifters, the playing-fingers engageable therewith at different heights, a movable fulcrum-bar carrying said fingers, standards, and guide-rods endwise movable in said standards, supporting-bearings for said fulcrum-bar adjustably secured on said guide-rod, and a controlling means, substantially as described, for moving said guide-rods within the standard for throwing the fingers into and out of playing contact.

10. In a piano-player, the combination with the finger-actuating pitmen having a plurality of finger-engaging notches or detents, a 100 series of disengageable fingers, and the adjustably-supported fulcrum-bar carrying said fingers; of an evener device adapted for supporting the finger ends in serial alinement when disengaged from the lifters.

105 11. In a piano-player, the combination with the fulcrum-bar carrying the fingers, the standing guide-rod and the bearing-piece adjustable on said guide-rod and having an arm upon which said fulcrum-bar is supported; 110 of a set-screw threaded into said arm endwise and impinging against the guide-rod, and a collar-nut threaded upon said set-screw and impingeable against said fulcrum-bar, for the purpose set forth.

115 12. In a piano-player, in combination with the notched finger-actuating lifters, the adjustable fulcrum-bar carrying the fingers, the adjustable bar-supporting bearing-piece, and standard guide-rods; of a spring-pressed stud arranged in said bearing-piece, and a guide-standard having lugs or recesses for coacting with said stud in corresponding relation to the detents of the lifters, for the purpose set forth.

125 13. In a piano-player, a finger or playing lever having a presser-head consisting of a semicylindrical cushion-faced block transversely secured to a metal spring, the opposite end of said spring-arm being connected 130 by fastening devices to the under side of the finger at a distance from its end, and an adjusting-screw arranged through the end of the finger, and impinging upon the spring-

plate at the back of the head, substantially as shown and described.

14. In an automatic piano-player, the combination, of a finger-actuating member having a plurality of engaging detents, a series of playing-fingers having ends adapted for engaging therewith, a fulcrum-bar carrying said fingers, and fulcrum-bar supports that afford horizontal movement and vertical ad-

justment at each end of said fulcrum-bar, and means for independently confining the parts at adjusted positions.

Witness my hand this 22d day of November, 1901.

FRANK C. WHITE.
